UNITED STATES PATENT OFFICE.

WILLIAM L. PROCUNIER, OF CHICAGO, ILLINOIS.

BIT AND TAP CHUCK.

1,117,241.

Specification of Letters Patent. Patented Nov. 17, 1914.

Original application filed June 16, 1911, Serial No. 633,531. Divided and this application filed November 14, 1913. Serial No. 800,919.

To all whom it may concern:

Be it known that I, WILLIAM L. PROCUNIER, a citizen of the United States, residing at Chicago, in the county of Cook and State of Illinois, have invented new and useful Improvements in Bit and Tap Chucks, of which the following is a specification, reference being had to the accompanying drawings, forming a part thereof.

10 This invention relates to improvements in the tool-holding means of bit and tap chucks designed particularly for use in drilling and tapping machines.

15 The present application is a division of my application Ser. No. 633,531, filed June 16, 1911, and issued in Patent No. 1,037,796, dated September 3, 1912.

20 It consists of the features and elements described and shown in the drawings as indicated by the claims.

25 In the drawings:—Figure 1 is an elevation partly in section showing a chuck embodying this invention with a tap inserted in position for use therein. Fig. 2 is a transverse section taken as indicated at line 2—2 on Fig. 1. Fig. 3 is a section taken as indicated at line 3—3 on Fig. 1 with the cap nut removed.

30 The drawings illustrate a chuck provided with the usual tapered shank, A, and with a specially constructed friction drive inclosed in a casing, B, and described in detail in my above mentioned patent.

35 The present invention relates to means for holding the tool in the lower end of the chuck, such means being shown in section in Fig. 1. It is well known that absolute uniformity is not found in respect to the dimensions of the round shank, x, of the drill or 40 tap and the squared upper end, y, which is positively engaged for driving. The tool is preferably centered by some engagement of the shank at its round portion, x, and is preferably driven by a positive engagement 45 with its squared end, y; and it is important, therefore, that any device for engaging the tool should effect such engagement positively and definitely both at the round portion and at the squared portion, and that neither engagement should forestall or defeat the other. For this purpose I provide in the 50 element, 1, a conical downwardly opening cavity, 1^a, while the element, 1, is exteriorly threaded to receive an interiorly threaded 55 follower, 2, having in its lower end a coni-

cal upwardly opening cavity, 2^a, preferably of the same taper as the conical cavity, 1^a. In the conical cavity, 1^a, there are lodged two jaws, 3, 3, exteriorly tapered conically to fit approximately the taper of the conical chamber, 1^a, and having their meeting faces notched to engage the squared end, y, of the tool shank of the customary form as illustrated. The two jaws, 3, 3, are engaged with the element, 1, for positive rotation thereby 60 by means of the cross pin, 4, which is inserted through the upper, smaller end of the jaws and engages a diametrically positioned longitudinal rift, 1^b, in the said conical chamber extending across the lower end 65 of the element 1. In the conical cavity of the follower, 2, there are lodged two semi-conical jaws, 5, 5, notched on their meeting faces for engaging the round portion, x, of the tool shank. With this construction it 70 will be observed that when the tool is inserted through the lower central aperture, 2^b, of the follower, 2, and up between the jaws, 5, 5, and then on up between the jaws, 3, 3, the rotation of the follower across it 75 on to the element, 1, will cause the jaws, 5, 5, whose upper faces rest up against the lower faces of the jaws, 3, 3, to force said jaws, 3, 3, up into their conical seat in the element, 1, until said jaws are closed upon 80 the squared end, y, of the tool, and that if when this happens the jaws, 5, 5, have not yet closely grasped the round shank, x, of the tool, the follower, 2, can be still further 85 screwed up until said round portion is thus 90 firmly grasped by the lower jaws. On the other hand, if the jaws, 5, 5, become closed firmly upon the round portion of the shank before the jaws, 3, 3, have firmly grasped the squared end, the follower can be screwed up 95 until the latter engagement is perfectly effected. Whenever, therefore, the operator finds the follower tight he is thereby assured that the tool is not only grasped firmly at its squared end for positive driving, but is 100 also grasped firmly at its round shank for centering. And this result will be obtained regardless of any ordinary variations from the standard in the size of either portion of the tool shank.

105 I claim:—

1. A chuck comprising a tool-holding member having a tapered cavity in one end and a centrally apertured follower, adapted to be screwed onto said end and having its 110

- cavity tapered to the central aperture, said two elements having their tapered cavities facing each other, base to base; a pair of tapered jaws in each of said tapered cavities, 5 the members of each pair having their proximate faces adapted for engaging a tool between them, and means for positively engaging the jaws in the first mentioned cavity with said first mentioned element for rotation therewith.
2. A chuck comprising an element having in one end a tapered cavity widest at the end, and a follower screwed onto said end and having a tapered cavity merging at its 15 smaller end in an axial aperture through the end of the cap nut; coöperating tool gripping jaws in each of said cavities, tapered to fit the respective cavities, those in one cavity meeting those in the other cavity base to 20 base; and means for engaging the jaws in the first mentioned cavity with the first mentioned element for rotation therewith.
3. A chuck comprising a tool holding element having in one end a tapered cavity and 25 having a longitudinal slot opening into such cavity; a follower screwed onto said ele-

ment, having a central aperture and a tapering cavity merging at its smaller end in such aperture and having its larger end or base facing the larger end or base of the cavity in 30 the first element; a pair of tool gripping jaws in the first mentioned tapering cavity tapered to fit the same; a pin which connects said jaws and engages the longitudinal slot mentioned, for rotating the jaws with 35 said first mentioned element, and a pair of tool gripping jaws lodged in the cavity of the cap and tapered to fit the same, the larger bases of the two pairs of tapering jaws resting against each other; whereby the 40 cap or follower being screwed onto the first mentioned element causes both pairs of jaws to grip an axially positioned tool extended between both pairs.

In testimony whereof I have hereunto set 45 my hand at Chicago, Illinois, this 8th day of November, 1913.

WILLIAM L. PROCUNIER.
